TETHERED BALL GAME DEVICE

Sandy Lang, Chicago, Ill.

Application October 30, 1946, Serial No. 706,681

3 Claims. (Cl. 273—97)

1

My invention relates to a toy having two cups with a ball attached therebetween, so that skill may be employed to move the ball from one cup and catch it in the other cup, and then from the second cup to the first cup, and so on as long as desired.

It is among the objects of my invention to teach pressure, movement, aim and patience to a user and to provide a toy which will furnish amusement, rhythm, poise and increased confidence with resultant success to the player. My invention also contemplates such other objects, advantages, and capabilities as will later more fully appear and which are inherently possessed by my invention.

While I have shown in the accompanying drawings a preferred embodiment of my invention, yet it is to be understood that the same is susceptible of modification and change without departing from the spirit of my invention.

Referring to the drawings, Fig. 1 is a top plan view of the toy embodying my invention; Fig. 2 is a side elevational view of my toy with movements indicated in dotted lines and Fig. 3 is a top perspective view of my toy.

The embodiment selected to illustrate my invention comprises an elongated base 10 having an outer portion 11 and an opposite inner handle portion 12. Adjacent the end of outer portion 11 is attached cup 13. Inwardly from cup 13, spring board 14 has its inner portion attached to outer portion 11 of base 10. A block 15 is attached to outer portion 11 somewhat nearer the center of base 10. The upper surface 16 of block 15 is inclined diagonally upwardly and supports a portion of spring board 14 to which it is attached. Spring board 14 continues past block 15 at a diagonally upward angle to a free upper end 17. Slightly below end 17, cup 18 is attached to spring board 14.

A cord 19 is attached on one end to spring board 14 at 20, which is half way between cups 13 and 18. The other end of cord 19 is attached to ball 21 at its middle inner portion.

Each of cups 13 and 18 has a built up bottom 22 and an opening 23 slightly larger than the diameter of ball 21.

Free end 17 of spring board 14 ends sufficiently short of the inner end of handle portion 12 of base 10 so that a player can grasp the end of handle portion 12 in his hand and place his thumb on free end 17.

Cord 19 is of such length as to just permit ball 21 to reach and lie in either of cups 13 and 18. 55

When ball 21 is in either cup 13 or 18, cord 19 is taut.

Let us assume ball 21 is in cup 18. The player presses down with his thumb on free end 17 of spring board 14 and lets go. If the pressure has been correctly applied and the aim of the player is true, ball 21 will travel to and lodge in cup 13. The player then throws upwardly on handle 12 and if properly done, the force will throw the ball back into cup 18. This is repeated and provides a rhythmic series of sounds as well as successful moves and catches.

The force exerted in impelling ball 21 in either direction must be sufficient to cause ball 21 to move rapidly from one cup upwardly and in the direction of the other cup. Centrifugal force then causes ball 21 to move in an arc from one cup to the other, with cord 19 remaining taut. The arc of movement has as its ends cups 13 and 18, its center point 20, and its radius cord 19. If the amount of force is sufficient and its direction in the line of base 10, the ball will not fail to move from one cup to the other.

In returning ball 21 from cup 13 to cup 18, 25 the resilience of spring board 14 might cause ball 21 to become dislodged after it has entered the cup. This can be avoided if the operator depresses free upper end 17 of spring board 14 with his thumb, thus lessening the resilience and preventing the ball from bouncing out of cup 18.

Having thus described by invention, I claim:

1. A toy comprising an elongated base having an outer portion and an opposite handle portion, a base cup attached to said outer portion adjacent the end thereof, a spring board attached to said outer portion inwardly from said cup, a block attached to said base and supporting said spring board at a diagonally upwardly extending angle, said spring board having an outer free end, spaced above and shorter than said handle portion, a spring board cup attached to said free end, a cord attached on one end to said spring board half way between said cups, and a ball attached to the other end of said cord, said cord 35 of only such a length as to permit said ball to reach either of said cups, and said cups of such size as to receive and permit removal of said ball, said spring board adapted upon pressure to move said ball from the spring board cup to the base cup, and said handle adapted upon force being applied to return said ball from said base cup to said spring board cup said ball adapted upon continued reciprocation between said cups to produce with said cups a rhythmic series of sounds.

2. A toy comprising a base, a spring board mounted on said base, a cup attached to the outer portions of each of said base and spring board, a cord having one end anchored half way between said cups, a ball attached to the outer end of said cord, said cord of only such a length as to permit said ball to reach either of said cups, and said cups of such size as to receive and permit removal of said ball, said spring board adapted upon pressure to move said ball from the spring board cup to the base cup, and said base adapted upon force being applied to return said ball from said base cup to said spring board cup. 10

3. A toy comprising a base, a spring board mounted on said base, the outer portions of each of said base and spring board having ball receiving means, a cord having one end anchored half way between said receiving means, a ball attached to the outer end of said cord, said cord of only such a length as to permit said ball to 15 20

reach either of said receiving means, and said receiving means of such size as to receive and permit removal of said ball, said spring board adapted upon pressure to move said ball from the spring board receiving means to the base receiving means and said base adapted upon force being applied to return said ball from said base receiving means to said spring board receiving means. 5
